(57) **CLAIM**

The ornamental design for an organic material collector substantially as shown and described.

DESCRIPTION

FIG. 1 is an isometric view of an organic material collector in accordance with the present disclosure;

FIG. 2 is a front view of the organic material collector of FIG. 1;

FIG. 3 is a back view of the organic material collector of FIG. 1;

FIG. 4 is a left side view of the organic material collector of FIG. 1;

FIG. 5 is a right side view of the organic material collector of FIG. 1;

FIG. 6 is a top view of the organic material collector of FIG. 1; and,

FIG. 7 is a bottom view of the organic material collector of FIG. 1.

The broken lines in the figures show portions of the organic material collector, which form no part of the claimed design.

1 Claim, 6 Drawing Sheets
